Patented Apr. 22, 1958

182,598

MOTOR VEHICLE INSTRUMENT PANEL

Gene R. Kiddon, Ann Arbor, Mich., assignor to Ford Motor Company, Dearborn, Mich., a corporation of Delaware

Application March 19, 1956, Serial No. 40,675

Term of patent 7 years

(Cl. D14—6)

FIG. 1

FIG. 2

FIG. 3

Figure 1 is an elevational view of a motor vehicle instrument panel, showing my new design;

Figure 2 is a perspective view, the broken line showing of portions of a motor vehicle being for purposes of illustration only; and

Figure 3 is a sectional view taken along line 3—3 of Figure 2.

I claim:

The ornamental design for a motor vehicle instrument panel, substantially as shown and described.
